UNITED STATES PATENT OFFICE

LOUIS A. GEBHARD, OF WASHINGTON, DISTRICT OF COLUMBIA, ASSIGNOR TO WIRED RADIO, INC., OF NEW YORK, N. Y., A CORPORATION OF DELAWARE

ADJUSTABLE INDUCTANCE SYSTEM

Application filed January 25, 1929. Serial No. 335,111.

My invention relates to inductance systems in general and more specifically to inductance systems employed in high frequency signaling.

5 An object of my invention is to provide an inductance system adapted to include a wide range of inductance values either of which may be selectively employed at will.

Another object of my invention is to provide 10 an inductance system whereby the inductance is varied at will in relatively small amounts.

Still another object of my invention is to provide 15 an inductance system wherein the inductance associated with an external circuit may be varied in relatively small steps and wherein a wide range of inductance values are readily obtainable.

Other and further objects of my invention 20 are to provide certain structural features whereby the inductance system is adaptable to wide application as more fully set forth in the specification following and illustrated in the accompanying drawing wherein:

25 Figure 1 shows an end elevation and Fig. 2 shows a side elevation of the adjustable inductance system of my invention.

It is frequently necessary or desirable to 30 employ an adjustable inductance for high frequency transmitting systems, laboratory experimentation and other varied applications. In inductance systems designed to be employed in combination with high frequency electrical circuits it is necessary that 35 the losses be reduced to a minimum. Losses arise most frequently in long connections to the inductance proper or through certain switching arrangements for effecting a variation in the amount of inductance connected 40 to the external circuit. By external circuit is meant that circuit with which the inductance is to be employed, such as a thermionic tube, for instance. Losses in addition to the above mentioned are frequently present 45 where a portion of a given inductance is connected to the external circuit and a large portion, that which is not immediately in use, having a magnetic field which is of no useful value at this adjustment. A better understanding 50 of my invention can be had from

the specification following and by referring to the accompanying drawing.

Fig. 1 of the accompanying drawing shows an end view of the adjustable inductance system of my invention. A plurality of individual inductance coils are arranged concentrically around a shaft and adapted to rotate therewith. The inductances are shown as four in number, however any number of coils may be employed. Inductance coils 1, 55 2, 3 and 4 are supported on a common circular frame member 9 and supported individually by coil forms or spacing members 5, 6, 7 and 8 respectively.

Members 5, 6, 7 and 8 are secured to frame 65 member 9. Frame member 9 also supports contact members 10, 11, 12, 13, 14, 15, 16, 17, 18, 19, 20 and 21. These contact members are directly supported by insulating members more fully illustrated in Fig. 2 to be referred 70 to later in this specification. Stationary contacts 22 are provided adjacent to the above mentioned contact members and adapted to selectively engage therewith at the will of the attendant operator. Frame member 9 is 75 supported by and secured to a shaft 23 which rests in suitable bearings provided in member 28. A section of member 9 is broken away to more clearly illustrate a "stop" or 80 step by step ratchet mechanism which comprises a disk 24 having a notched periphery with which an arm 25 engages. Arm 25 has sufficient resilient properties to exert a retaining force against the movement of disk 24 which is secured to shaft 23. Disk 24 is secured to shaft 23 in such a manner that arm 25 engages with the notches in the periphery thereof corresponding to the position of the individual coils. Coils 1, 2, 3 and 4 are therefore held in the position set until voluntarily 85 moved from this position by the act of the attendant operator. Contact members are carried by arm 25 adapted to contact with member 25a. The two contact members may be supported and electrically insulated from each other by a supporting block 25b of insulating material. In addition to the positive stop mechanism for retaining the respective coils in the proper position the contact members associated with and adjacent to arm 25 90 95 100

may control any electrical circuits. It is obvious that such circuits may include the energy supply circuits of thermionic tubes and the like whereby the potential is positively 5 and immediately removed from the thermionic tube when a change of inductance is effected.

Fig. 2 is an illustration showing a side elevation of the adjustable inductance system 10 of my invention. Reference characters herein correspond to those employed in Fig. 1. This illustration shows movable contact members 11a, 11b, 13a, 13b, 14a, 14b, 15a, 15b, 16a, 16b and 17a, 17b not shown in Fig. 1. 15 These contact members are associated with the respective inductance coils in a manner suited to the particular application. In the illustration shown in Fig. 2, inductance coil 2 is supported on coil form 6, secured to 20 frame member 9a. Form 6 is shown in section with that section removed which would normally be secured to frame member 9. Frame member 9a is similar to frame member 9 shown in Fig. 1 comprising 25 a circular disk. It is obvious that members 9 and 9a may be of any suitable design such as crossed star shaped members. Insulating bars 13c, 14c and 15c are spacially positioned around the periphery of members 30 9 and 9a and substantially at right angles to their planes. Contact members 13, 13a and 13b are suitably spaced on insulating member 13c and are electrically connected to different portions of inductance 2. Contact 35 members 14, 14a and 14b are spacially positioned on insulating member 14c and electrically connected to different portions of inductance 2 or other than those of members 13, 13a and 13b. In like manner contact 40 members 15, 15a and 15b are spacially positioned on member 15c and electrically connected to different turns of inductance 2 other than the connections of members 13, 14, 13a, 13b, 14a and 14b. Contact members 45 13a, 14a and 15a are usually connected to substantially the same turn of inductance 2 when the inductance is employed in an oscillatory circuit arrangement, it is obvious, however, that these connections may be in any manner 50 to any portion of the inductance.

Similarly, contact members 16, 16a, 16b, 17, 17a, 17b and others are electrically associated with inductance coil 3. Each of the individual inductance coils are in this manner 55 associated with individual contact members. In this manner it is possible to obtain a plurality of different inductance values from each of the individual inductance coils. A greater change in the inductance value to 60 be connected to the external circuit is obtained when frame member 9—9a is moved sufficiently to bring a different inductance coil in position. An indicating dial 26 and control handle 27 are secured to shaft 23. 65 Axle 23 is supported by members 28 and 29,

the latter provided with suitable bearings through which shaft 23 rests. Stationary contacts 22, 22a and 22b are positioned in such a manner as to be engaged with the contact members carried by frame member 70 9—9a.

The operation and advantages of the adjustable inductance system of my invention may be understood by more detailed reference to Fig. 1. The position of the inductance coils shown in this illustration is that where inductance 3 is connected to the stationary contact members. This position is secured by locking mechanism 24—25. The retaining force of locking mechanism 24—25 80 may however be overcome and the inductance 3 moved either in a clockwise or anticlockwise direction. Either of the last mentioned positions would connect a different value of inductance to the stationary contact members. The number of groups of contacts associated with a particular coil may be greater than or less than the three groups shown. It is advantageous, however, to employ such connections to the respective turns of the inductance coil as would not leave a great 85 number of unused turns or a large portion of the coil as a "dead end."

The "dead end" is herein employed as designating that portion of the inductance 90 not immediately connected to the external circuit. It is therefore in accordance with efficient design that the number of different adjustments of inductance provided for a given inductance coil not be great enough to 100 leave a large portion of the respective inductance out of the circuit. When an increase or a decrease in the amount of inductance is desired beyond the range of the particular coil in the circuit, another coil is moved into position. In this manner losses are reduced to a 105 minimum.

I realize that many modifications of my invention are possible without departing from the spirit of my invention. The number of individual inductances or the design of the inductances as shown herein is not to limit my invention and it is to be further understood that the embodiments of my invention shall not be restricted by the foregoing 110 specification or by the accompanying drawing but only by those restrictions imposed from the appended claims.

What I claim as new and desire to secure 115 by Letters Patent of the United States is as follows:

1. In an inductance system, a fixed frame, a rotatable frame supported by said fixed frame and comprising lateral members, a plurality of inductors carried by said rotatable frame, rotor contactors carried by said lateral members and in electrical relation with said inductors, and fixed contactors carried by said fixed frame and adapted to engage said rotor contactors as said rotatable frame is rotated. 125 130

- elements being positioned and adapted to be respectively engaged as said rotor unit is rotated, whereby electrical connection may be made selectively to each of said inductor units. 5
8. In an inductance system, a rotor unit comprising end supporting members and lateral rib members carried by said end members, a plurality of coil form members extending between and carried by said end members, a central supporting shaft, means for rotating said rotor unit, a plurality of helical single layer inductor elements formed of electrical conductor supported respectively on said coil form members, rib contact elements carried by said lateral rib members and extending outwardly from the axis of said rotor element, a supporting base frame provided with bearings in which said central shaft is carried, fixed contact elements carried by said base frame, inductor contact elements attached to said inductor elements at separate points thereof, means for connecting said inductor contact elements respectively to adjacent rib contact elements, said rib contact elements and fixed contact elements being positioned and adapted to be respectively engaged as said rotor unit is rotated, locking means for exerting a retaining force against the movement of said rotor unit when said rib contact elements engage said fixed contact elements, and switching means operably associated with said locking means, whereby electrical connection may be made selectively to each of said inductor units. 10 15 20 25 30 35 40 45 50 55 60 65 70 75 80 85 90 95 100 105 110 115 120 125
9. In an inductance system, a rotor unit comprising end supporting members and lateral rib members carried by said end members, a plurality of coil form members extending between and carried by said end members, a central supporting shaft, means for rotating said rotor unit, a plurality of helical single layer inductor elements having different values of inductance supported respectively on said coil form members, rib contact elements carried by said lateral rib members and extending outwardly from the axis of said rotor element, a supporting base frame provided with bearings in which said central shaft is carried, fixed contact elements carried by said base frame, inductor contact elements attached to said inductor elements at separate points thereof, means for connecting said inductor contact elements respectively to adjacent rib contact elements, said rib contact elements and fixed contact elements being positioned and adapted to be respectively engaged as said rotor unit is rotated, whereby electrical connection may be made selectively to each of said inductor units. 35 40 45 50 55 60 65 70 75 80 85 90 95 100 105 110 115 120
10. In an inductance system, a rotor unit comprising end supporting members and lateral rib members carried by said end members, a plurality of coil form members extending between and carried by said end members, a central supporting shaft, means for rotating said rotor unit, a plurality of helical single layer inductor elements sup- 60 65 70 75 80 85 90 95 100 105 110 115 120 125
- ported respectively on said coil form members, rib contact elements carried by said lateral rib members and extending outwardly from the axis of said rotor element, a supporting base frame provided with bearings in which said central shaft is carried, fixed contact elements carried by said base frame, inductor contact elements attached to said inductor elements at separate points thereof, means for connecting said inductor contact elements respectively to adjacent rib contact elements, said rib contact elements and fixed contact elements being positioned and adapted to be respectively engaged as said rotor unit is rotated, locking means for exerting a retaining force against the movement of said rotor unit when said rib contact elements engage said fixed contact elements, and switching means operably associated with said locking means, whereby electrical connection may be made selectively to each of said inductor units. 70 75 80 85 90 95 100 105 110 115 120 125
11. In an inductance system, a rotor unit comprising end supporting members and lateral rib members carried by said end members, a plurality of coil form members extending between and carried by said end members, a central supporting shaft, means for rotating said rotor unit, a plurality of helical single layer inductor elements supported respectively on said coil form members, rib contact elements carried by said lateral rib members and extending outwardly from the axis of said rotor element, a supporting base frame provided with bearings in which said central shaft is carried, fixed contact elements carried by said base frame, inductor contact elements attached to said inductor elements at terminal points thereof, means for connecting said inductor contact elements respectively to adjacent rib contact elements, said rib contact elements and fixed contact elements being positioned and adapted to be respectively engaged as said rotor unit is rotated, whereby electrical connection may be made selectively to each of said inductor units. 90 95 100 105 110 115 120 125
12. An interchangeable electrical circuit controlling instrument comprising, a plurality of electrical devices, a rotatable member upon which said devices are mounted contact posts electrically connected with said devices, said posts projecting from said rotatable member, said posts located upon the rotatable member in different planes and movable with said member in said different planes, a member rigidly positioned in spaced relation with the rotatable member, and contact plates located upon said rigid member and projecting therefrom into the path of movement of said posts for completing electrical circuits including either of said electrical devices. 115 120 125

LOUIS A. GEBHARD.
